FOLDING TRAY TABLE

Russell B. Wilson, Denver, Colo.

Application September 26, 1955, Serial No. 38,091

Term of patent 14 years

(Cl. D33—14)

Fig. 1 is a perspective view of a folding tray table showing my new design;

Fig. 2 is an end elevational view thereof; and

Fig. 3 is a view showing the tray raised to disclose the upper portions of the leg members.

I claim:

The ornamental design for a folding tray table, as shown.
